Primary Examiner — T. Chase Nelson*Assistant Examiner* — Ania Aman*(74) Attorney, Agent, or Firm* — Dykema Gossett PLLC(57) **CLAIM**

The ornamental design of a motor housing for a linear actuator, as shown and described.

DESCRIPTION

FIG. 1 is a perspective bottom view of a motor housing for a linear actuator showing my new and ornamental design, FIG. 2 is a perspective top view thereof,

FIG. 3 is a perspective top view similar to FIG. 2 with the cover removed,

FIG. 4 is a top plan view thereof with the cover removed,

FIG. 5 is a bottom plan view thereof,

FIG. 6 is a left side view thereof,

FIG. 7 is a right side view thereof,

FIG. 8 is a rear end view thereof; and,

FIG. 9 is a front end view thereof.

1 Claim, 4 Drawing Sheets**FIG. 1**

FIG. 2

FIG. 3

FIG. 4**FIG. 5**

FIG. 6**FIG. 7****FIG. 8****FIG. 9**
